MATTRESS BORDER STITCHING MACHINE

Dwight N. Kelly, Chicago, Ill., assignor to A. Brandwein & Company, Chicago, Ill., a corporation of Illinois

Application January 30, 1942, Serial No. 428,842

11 Claims. (Cl. 112—117)

The invention relates generally to stitching machines and more particularly to a machine for making parallel lines of stitching on mattress borders or the like.

The invention has among its objects the production of such a machine for securing a plurality of plies of material to one another by a plurality of rows of parallel lines of stitching, which machine is relatively simple in construction having a minimum number of parts and which is very dependable and fast in operation.

Another object of the invention is the production of such a machine wherein the stitching mechanism is continuously actuated eliminating the necessity of cutting or breaking the threads at the end of each line of stitching.

A further object of the invention is the production of such a machine which is so constructed that it may be readily adjusted to form lines of stitching of various lengths and spaced apart various distances.

A further object of the invention is the production of novel means for holding the material in position while being stitched which means may be readily used in conjunction with a border of varying thicknesses and widths.

Other objects of the invention are the improvements in stitching mechanisms of the type described, in sundry details as will be apparent to those skilled in the art from the disclosure hereinafter given.

To this end my invention consists in the novel construction, arrangement and combination of parts herein shown and described and more particularly pointed out in the claims.

In the drawings wherein like reference characters indicate like or corresponding parts:

Fig. 1 is an end elevational view of a machine embodying the present invention with a portion of the supporting framework broken away;

Fig. 2 is a plan sectional view taken approximately on the line 2—2 of Fig. 1;

Fig. 3 is a rear elevational view of the machine;

Fig. 4 is a sectional view taken approximately on the line 4—4 of Fig. 2;

Fig. 5 is a plan view of the hold-down mechanism taken approximately on the line 5—5 of Fig. 3;

Fig. 6 is an end elevation of the stitching machine hold-down means;

Fig. 7 is a side elevational view of the same; and

Fig. 8 is a sectional view taken substantially on the line 8—8 of Fig. 1.

The machine illustrated in the drawings is adapted to stitch a plurality of plies together, as for example, in a mattress border or boxing wherein the line of stitching extends transversely across the boxing at spaced intervals to produce a fluted effect. The boxing usually comprises an outer boxing strip, an inner fabric strip and padding interposed between the two, the padding being normally narrower than the outer ply.

The machine broadly comprises a stitching mechanism supported upon a suitable frame and longitudinally movable across the latter, the material stitched being intermittently fed transversely through the stitching mechanism which is designed to stitch regardless of the direction in which the stitching mechanism is moving relative to the material being stitched, and is in continuous operation.

The mechanism for feeding the material is synchronized with the stitching mechanism so that the former will remain inoperative while the stitching mechanism travels across the material. As the stitching mechanism reaches the end of its travel the material will be fed forward thereby longitudinally stitching adjacent the edge of the material. Upon stopping of the feeding mechanism the sewing mechanism will begin its return movement across the material forming another line of stitching. As at the end of the previous stitch the material will be fed as the sewing mechanism reaches the end of its travel thereby forming a second longitudinally extending line of stitching at the opposite side of the material, after which, the cycle will again be repeated. It will be noted that with this construction the stitching mechanism, regardless of carriage movement, is continuously in operation so that means for breaking or cutting of the thread is eliminated. Not only is means for performing the latter functions omitted, but also means for starting and stopping the stitching mechanism with the needle in raised position at the end of a line of stitching. As a result, the machine is relatively simple in construction requiring a minimum number of parts.

Referring to the drawings and more particularly to Figs. 1, 2 and 3, 1 indicates generally a supporting frame comprising legs 2 connected adjacent their upper ends by end members 3 and front and rear members 4 and 5. Extending between the front and rear members 4 and 5 are a pair of spaced ways 6, the latter being rectangular in cross section as shown in dotted lines in Fig. 3. Supported on the ways 6 by grooved rollers 7 is a carriage, indicated generally by the nu-

meral 8 which is movable back and forth on the ways 6. Mounted on the carriage 8 is a stitching mechanism indicated generally by the numeral 9 of general construction which is adapted to stitch in any direction, forward, backward or laterally.

The stitching mechanism

The stitching mechanism is operatively connected to a motor 11, the motor being mounted on suitable cross members carried by the supporting frame 1, and connected to a countershaft 12 by suitable means such as pulleys or sheaves 13 and 14 and the belt 15, the countershaft 12 being journaled in suitable bearings 16 and 17, the latter in turn being supported by respective cross members 18. Pivotedly related, at one end, to the bearing 17 is an arm 19, the latter being rotatable relative the shaft 12 about the axis of the latter. The free end of the arm 19 is pivotally connected as shown at 20 to a second arm 21 which is pivotally related at its opposite end to a gear box 22, supported from the lower side of the carriage 8. Carried by one of said arms and rotatable on the common axis thereof is a pair of pulleys or sheaves 23 and 24 respectively, the pulley 23 being connected to the countershaft 12 by a pulley 25 and belt 26. The pulley 24, in like manner, is connected to the drive shaft 27, journaled in the gear box 22, by a pulley 28 and belt 29. The pivotal connection of the arm 21, the gear box 22 and shaft 27 have a common axis so that as the carriage 8 is reciprocated on the ways 6, the arms 19 and 21 are free to move about their respective pivotal connections thereby providing a traveling connection between the countershaft 12 and the shaft 27. Obviously, chains and sprockets, or other suitable means may be employed in place of the belts and pulleys. The shaft 27 is operatively connected to a transverse shaft 31 by suitable gearing carried in the gear box 22, the latter being of ordinary construction, the details of which are not shown. The shaft 31 in turn is connected to the main drive shaft 32 of the stitching mechanism 9 by pulleys 33 and 34 mounted on the respective shafts and the belt 35. Thus, the drive shaft 32 is positively connected to the motor 11 at all times regardless of the movement or position of the carriage 8 and stitching mechanism 9 with respect thereto.

The reciprocating mechanism

Also mounted on the cross members 18 is a reduction gear box indicated generally by the numeral 41, the internal details of which are not shown as they are of the usual construction. Extending vertically from the gear box 41 is a shaft 42 which is operatively connected through the reduction gearing in the box 41 to the countershaft 12 by gears 43 and 44 carried by the shaft 12 and gear box 41, respectively. Rigidly mounted on the shaft 42 is a plate 45 which is operatively connected to the carriage 8 by a link member, indicated generally by the numeral 46, which is pivotally connected at one end to the plate 45 and at its other end to the column or projection 47 rigidly carried by the carriage 8. The pivotal connection between the link 46 and plate 45 is offset from the axis of the shaft 42 whereby the plate 45 in effect forms a crank arm, the effective length of which may be varied by radially moving the connecting member 48 in the slot 48a in the plate 45. The member 48

may be locked in position on the plate by means of the nut 49 and, if desired, an adjustment stud 50 and nut 51 may be provided to facilitate a relatively fine adjustment of the member 48 relative the plate 45. Obviously, as the plate is rotated by the motor 11 and connecting mechanism the carriage 8 will be reciprocated back and forth on the ways 6. As illustrated in Figs. 1 and 8, the link member 46 is provided with a slot 52 through which the pin 53, carried by the member 48, extends so that there will be some lost motion between the plate 45 and link 46 at each end of travel of the carriage. The latter will therefore remain in a stationary position at each end of a line of stitching while said lost motion is taken up by the mechanism, the duration of this stationary period being controlled by the length of the slot 52. The link member 46 is preferably made in two sections, 46a which is threaded into the second section 46b and locked in position with respect thereto by a lock nut, thereby providing a means of lengthening or shortening the link 46 to provide an additional means of adjustment. It will be apparent that the amount of travel of the carriage 8 and stitching mechanism 9 will be readily controlled by the positioning of the pivotal connection between the link 46 and plate 45 with respect to the axis of the shaft 42, while the position of the stitching mechanism at the beginning and end of each stroke may be controlled by adjusting the link 46.

The feeding mechanism

35 Mounted on a suitable cross member extending between the front and rear connecting members 4 and 5 are a pair of standards designated generally by the numeral 55. Journaled in the standards or uprights 55 is a lower roller 56 and 40 an upper roller 57, the latter being supported for movement toward and away from the roller 56 but normally urged towards the latter by a spring 58 or other suitable means which may be adjusted by the screw 59. The rollers 56 and 57 45 initially receive the materials being fed as clearly shown in Fig. 5 after which the material passes through a second pair of rollers 61 and 62 which are journaled in uprights or standards 63, which 50 are suitably supported by the frame-work of the machine. The rollers 61 and 62 are operatively connected by a pair of meshed pinions 65 and 66 rigidly carried by the roller shafts 67 and 68 respectively, the shaft 67 being also provided with a ratchet wheel 69 rigidly secured thereto. Supported by the lower end member 71 and cross member 72 is a reduction gear box 73 having a driving shaft 74 connected to the countershaft 12 by a gear 75 meshing with the gear 60 43 on the shaft 12.

Extending from the gear box 73 is a driven shaft 76 having a cam 77 rigidly secured thereto. The latter is engageable with a roller 78 rotatably carried by an arm 79 which in turn is pivotally mounted on an upright 81 by means of the bolt 82 as illustrated in Fig. 4, the upright 81 being rigidly mounted on the member 83 carried by the lower end member 71. A spring 84 urges the arm 79 upwardly, thereby tending to maintain the roller 78 in engagement with the cam 77. Rotatable about the axis of the shaft 67 is a ratchet arm 85 having a pawl 86 thereon engageable with the teeth of the ratchet wheel 69, a flat spring 70 87 urging the pawl 86 into engagement with the

teeth of the wheel. The ratchet arm 85 is connected to the arm 79 by means of a link member 88 pivotally connected at its ends to the respective members 79 and 85. The link 88 is connected to the ratchet arm in such a manner that the pivotal connection between the link 88, and the arm 85 may be moved towards or away from the axis of the shaft 67 and locked in any desired position, thereby providing means of adjustment for varying the rotation of the feed rolls 61 and 62. Thus as the shaft 76 is rotated and with it the cam 71, the feed rolls will be intermittently rotated to feed the material being stitched through the stitching mechanism. The driving ratios between the motor 11 and the respective boxes 41 and 73 are such that the feed rolls 61 and 62 will be partially rotated each time the stitching mechanism arrives at the end of its travel in either direction.

The hold-down mechanism

To insure the material passing through the stitching mechanism lying flat and unwrinkled adjacent the needle while a line of stitching is formed, novel hold-down means is provided, the latter being illustrated in Figs. 3 and 5 of the drawings. This mechanism comprises a plate 89, above which are a pair of standards or lugs 90 secured by any suitable means to the respective uprights 55, a rod 91 extending between and secured to the respective standards 90. Centrally positioned with respect to the material passing through the stitching mechanism is a relatively heavy roller 92 rotatably carried by a pair of arms 93, the latter being pivotally secured adjacent their free ends to the rod 91, collars 94 being secured to the rod 91 to prevent lateral displacement of the arms 93 relative the material. Thus, the roller 92 is free to revolve about its own axis and also free to move up and down about the rod 91. The roller 92 compresses the material between it and the plate 89 and maintains the central portion of the material in proper position for stitching and prevents shifting of the same. Positioned on each side of the roller 92 is a shorter roller 95 freely rotatable about a shaft or stud 96 rigidly carried by an arm 97 which is pivotally supported adjacent its free end by the rod 91. The arms 97 and rollers 95 are urged downwardly towards the plate 89 to firmly engage the edges of the material by springs 98, the ends of which are secured to collars 99 rigidly secured to the rod 91 and the opposite ends extending at right angles, as shown at 101 to engage the respective arms 97. The tension of the springs 98 may be readily adjusted by rotating the collars 99 about the rods 91, the collars being locked in position on the rod by suitable set screws or the like so that any desired pressure may be exerted upon the fabric by the rollers 95. This construction is particularly desirable where the plies of material being stitched are of different widths, such as that illustrated in Fig. 5 of the drawings, wherein the boxing, indicated generally by the letter B, comprises an inner ply I and an outer ply O between which is positioned a layer of padding P, the latter being narrower in width than either of the plies I or O. Obviously, with such a boxing construction the roller 92 would not retain the edges of the plies I and O in proper position, even though the roller 92 were lengthened to overlie the entire boxing. However, with the present construction the spring actuated rollers 95 are free to move independently with respect to each other

and with respect to the roller 92 and to thereby securely hold the edges of the plies in proper position. It will be apparent that due to the size of the roller 92 it is heavy enough to maintain the central portion of the boxing in position without applying additional force to the roller by the use of springs or other means. The rollers 95 are also desirable where the padding extends entirely across the boxing to permit the edges of the boxing from flaring upwardly. To further assure smooth and efficient operation a novel pressure foot construction is employed on the stitching mechanism and comprises a longitudinally movable rod 111 carried by the stitching head 112, a suitable spring or the like urging the rod 111 downwardly towards the material being stitched. Secured to the free end of the rod 111 is a block 113 to which is rotatably secured a disk-like roller 114. The latter is preferably rounded slightly adjacent its forward edge, as shown at 115, to eliminate any possibility of the roller bunching the material as the latter is fed through the machine by the feed rolls 61 and 62. As shown in Figs. 5 and 6 the axis of the roller 114 is inclined slightly to position the lower edge of the roller in proper position with respect to the end of the needle.

The operation of the machine

30 In operation the material will be advanced a step and held in stationary position by the rollers and hold-down mechanism while the stitching head travels across the material, thereby forming a lateral line of stitching entirely across the boxing. As the stitching mechanism ends its travel it will remain in a stationary position for a predetermined period while the lost motion is taken up between the link 46 and the plate 45 which has been previously described. While the carriage is in such stationary position the feed rolls 61 and 62 will be partially rotated to advance the material one step and as the stitching mechanism is continually driven through the belts 26, 29 and 35 a longitudinal line of stitching will be formed upon or adjacent to the edge of the boxing. Simultaneous with the completion of the feeding movement of the material the lost motion in the reciprocating mechanism will have been taken up and the stitching head will then travel back across the material forming a second line of stitching laterally across the boxing. At the termination of this second line of stitching, the carriage will come to a rest as the lost motion is again taken up, during which stationary period the feed rolls 61 and 62 will again be partially rotated to feed the material another step, thereby forming a second longitudinally extending line of stitching adjacent the opposite edge of the boxing from that having the longitudinally extending line of stitching previously formed, and upon completion of the feeding movement the carriage will again start its travel to begin another complete cycle of operation.

65 It will be apparent that with the present construction the stitching mechanism is in continuous operation regardless of the movement of the carriage or material, thereby eliminating starting and stopping such mechanism at the end of each row of stitches cutting or breaking the thread etc., and as the stitching mechanism is operative during both forward and return movement of the carriage instead of merely during the forward movement, the boxing may be stitched in one-half the amount of time required

for stitching on a machine operating in one direction only.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a machine of the kind described the combination of a supporting frame, a pair of ways carried by said frame, a carriage movably carried by said ways, a stitching mechanism mounted on said carriage, a main drive shaft journaled in said frame, a gear box mounted on said frame having a driving and a driven shaft, spur gears operatively connecting said drive shaft and the driving shaft of said gear box, said driven shaft extending vertically and having a crank member carried by the upper end thereof, a link member pivotally connected at its respective ends to said crank arm and said carriage respectively, a shaft rotatably carried by said carriage operatively connected to said stitching mechanism for actuating the latter, means for operatively connecting said shafts, a pair of feed rollers geared to one another, a ratchet wheel carried by one of said rollers, a ratchet arm rotatable about the axis of said last mentioned roller having a pawl engageable with said ratchet wheel, a gear box having a driving and a driven shaft, said driving shaft having a gear thereon engageable with the gear on said drive shaft, a cam mounted on said last mentioned driven shaft, a lever pivotally supported at one end by said frame and having means thereon engageable with said cam, resilient means for urging said lever towards said cam, and a link member operatively connecting the free end of said lever and the free end of said ratchet arm.

2. In a machine of the kind described the combination of a supporting frame, a pair of ways carried by said frame, a carriage movably carried by said ways, a stitching mechanism mounted on said carriage, a main drive shaft journaled in said frame, a gear box mounted on said frame having a driving and a driven shaft, spur gears operatively connecting said main drive shaft and the driving shaft of said gear box, said driven shaft extending vertically and having a crank member carried by the upper end thereof, a link member pivotally connected at its respective ends to said crank member and said carriage respectively, a shaft rotatably carried by said carriage operatively connected to said stitching mechanism for actuating the latter, an arm operatively carried at one end by said carriage and rotatable about the axis of said stitching mechanism drive shaft, a second arm operatively carried at one end by said frame and rotatable about the axis of said main drive shaft, said arms being pivotally connected to one another at their free ends, driven means rotatable about the common pivot point of said arms, a belt member operatively connecting said main drive shaft and said driven means, and a second belt member connecting said driven means and said stitching mechanism drive shaft, means for feeding material through said stitching mechanism, and means for actuating said feeding means at the end of each forward and return movement of said carriage.

3. In a machine of the kind described the combination of a supporting frame, a pair of ways carried by said frame, a carriage movably carried by said ways, a stitching mechanism mounted on said carriage, a main drive shaft journaled in said frame, a gear box mounted on said frame having a driving and a driven shaft, spur gears operatively connecting said main drive shaft and the driving shaft of said gear box, said driven shaft extending vertically and having a crank carried by the upper end thereof, a link member pivotally connected at its respective ends to said crank member and said carriage respectively, a shaft rotatably carried by said carriage operatively connected to said stitching mechanism for actuating the latter, said shaft extending parallel to said main drive shaft, an arm operatively carried at one end by said carriage and rotatable about the axis of said stitching mechanism drive shaft, a second arm operatively carried at one end by said frame and rotatable about the axis of said main drive shaft, said arms being pivotally connected to one another at their free ends, driven means rotatable about the common pivot point of said arms, a belt member operatively connecting said main drive shaft and said driven means, and a second belt member connecting said driven means and said stitching mechanism drive shaft, a pair of feed rollers geared to one another, a ratchet wheel carried by one of said rollers, a ratchet arm, rotatable about the axis of said last mentioned roller, having a pawl engageable with said ratchet wheel, a gear box having a driving and a driven shaft, said driving shaft having a gear thereon engageable with the gear on said drive shaft, a cam mounted on said last mentioned driven shaft, a lever pivotally supported at one end by said frame and having means thereon engageable with said cam, resilient means for urging said lever towards said cam, and a link member operatively connecting the free end of said lever and the free end of said ratchet arm.

4. In a machine of the kind described the combination of a supporting frame, a pair of ways carried by said frame, a carriage movably carried by said ways, a stitching mechanism mounted on said carriage, a main drive shaft journaled in said frame, a reduction gear box mounted on said frame having a driving and a driven shaft, spur gears operatively connecting said main drive shaft and the driving shaft of said gear box, said driven shaft extending vertically and having a crank member carried by the upper end thereof, a link member pivotally and slidably connected at its respective ends to said crank arm and said carriage respectively, a shaft rotatably carried by said carriage operatively connected to said stitching mechanism for actuating the latter, said shaft extending parallel to said main drive shaft, an arm operatively carried at one end by said carriage and rotatable about the axis of said stitching mechanism drive shaft, a second arm operatively carried at one end by said frame and rotatable about the axis of said drive shaft, said arms being pivotally connected to one another at their free ends, pulleys rigidly carried by the respective shafts, a two sheaved pulley rotatable about the common pivot point of said arms, a belt operatively connecting the pulley on said main drive shaft and one of said sheaves and a second belt connecting the other sheave and the pulley on said stitching mechanism drive shaft, a pair of feed rollers geared to one another, a ratchet wheel carried by one of said rollers, a ratchet arm rotatable about the axis of said last mentioned roller having a pawl engageable with said ratchet

wheel, a gear box having a driving and a driven shaft, said driving shaft having a gear thereon engageable with the gear on said drive shaft, a cam mounted on said last mentioned driven shaft, a lever pivotally supported at one end by said frame and having means thereon engageable with said cam, resilient means for urging said lever towards said cam, and a link member operatively connecting the free end of said lever and the free end of said ratchet arm.

5. In a hold-down device of the kind described the combination of a base plate, a supporting member positioned above said base plate, a pair of arms rotatably carried at one of their ends by said supporting member, a hold-down roller carried by said arms adjacent the free ends of the latter and rotatable relative thereto, a second pair of arms carried at one of their ends by said supporting member and rotatable on the common axis of said first mentioned pair of arms, and a roller rotatably carried by each of said second mentioned arms, and a pair of springs, each spring having one of its ends operatively connected to one of said second pair of arms and at the other end to said supporting member for urging each of said last mentioned arms and its respective roller towards said base plate.

6. In a hold-down device of the kind described the combination of a base plate, a supporting member positioned above said base plate, a pair of arms rotatably carried at one of their ends by said supporting member, means for preventing axial movement of said arms relative said member, a hold-down roller carried by said arms adjacent the free ends of the latter and rotatable relative thereto, a second pair of arms carried at one of their ends by said supporting member and rotatable on the common axis of said first mentioned pair of arms, a roller rotatably carried by each of said second mentioned arms, the axes of the respective rollers being equidistant from the common axis of said arms relative to said supporting member, and a pair of springs, each spring having one of its ends operatively connected to one of said second pair of arms and at the other end to said supporting member for urging each of said last mentioned arm and its respective roller towards said base plate.

7. A hold-down device comprising a fixedly supported shaft a pair of arms carried at one end by said shaft, a hold-down roller carried by the opposite ends of said arms and freely rotatable relative to same, said arms being rotatable about the axis of said shaft, a second pair of arms rotatably carried by said shaft, rollers rotatably carried by the respective last mentioned arms and resilient means for urging said arms and rollers towards the material to be held, said last mentioned rollers being positioned adjacent the ends of said first roller.

8. In a machine of the kind described, the combination of a supporting frame, a pair of ways carried by said frame, a carriage movable on said ways, a stitching mechanism, means for intermittently feeding the material to be stitched through said mechanism, reciprocatory means having a

driving member and a link mechanism connected therewith and with said carriage for reciprocating said carriage on said ways, and lost motion means interposed between said drive member and said link mechanism for rendering said reciprocating means inoperative and to interrupt the movement of said carriage during actuation of the feeding means.

9. In a machine of the kind described, the combination of a supporting frame, a pair of ways carried by said frame, a carriage movable on said ways, a stitching mechanism mounted on said carriage, means for continuously actuating said stitching mechanism, means for reciprocating said carriage and mechanism including a rotatably driven member and a pitman member, means for rendering said reciprocating means inoperative at the beginning and end of each stroke of said pitman member to maintain said carriage stationary for a predetermined interval of time, and means for feeding the material to be stitched relative to said stitching mechanism while said carriage is in such stationary position.

10. In a machine for sewing rows of stitching on material at an angle with respect to the path of travel of said material while the latter is intermittently fed through the machine, the combination of a sewing mechanism movably carried for reciprocatory motion across the face of the material, of driving means including feed means to intermittently advance said material relative to said sewing mechanism, and operative means for reciprocating said sewing mechanism, said operative means comprising a movable member and a connecting member connected between said sewing mechanism and said movable member, and lost motion mechanism associated with one end of said connecting member to cause the sewing mechanism to dwell at predetermined intervals during the reciprocation thereof and at such intervals when said material is advanced relative to said sewing mechanism by said feed means.

11. In a machine for applying rows of stitching transversely to the movement of the material being stitched, the combination of a reciprocatory sewing unit, of drive mechanism including feed means for intermittently advancing said material through the machine, and reciprocatory means for moving said sewing unit, said reciprocatory means comprising a driven member revolving on a fixed axis of rotation, and a pitman connected at one end with said driven member and at the other end with said sewing unit, one of the connections of one of the ends of said pitman including lost motion mechanism to render said pitman inoperative at certain intervals in the cycle of operation of the machine and coincident with the periods when said material is advanced relative to said sewing unit by said feed means, said lost motion mechanism including adjustable means for varying the period of dwell of said sewing unit during the feed of the material.
